UNITED STATES PATENT OFFICE.

ROBERT O. WOOD, OF ELIZABETH, NEW JERSEY, ASSIGNOR OF ONE-HALF TO PITSER MILLER, OF ELIZABETH, NEW JERSEY.

DECORATIVE CANDLE AND MOUNTING THEREFOR.

Application filed February 23, 1924. Serial No. 694,528.

To all whom it may concern:

Be it known that I, ROBERT O. Wood, a citizen of the United States, and resident of Elizabeth, county of Union, State of New Jersey, have invented an Improvement in Decorative Candles and Mountings. Therefor, of which the following description, in connection with the accompanying drawings, is a specification, like characters on the drawings representing like parts in each of the several views.

This invention relates to articles for decorative and ornamental purposes in household use, and more particularly to a decorative device embodying a container tube of glass or like transparent material which contains colored fibrous material preferably unwoven, such for example as silk, processed cotton, thread yarn, floss and the like, the device thus constituted being preferably made up to simulate a candle in appearance and also adapted to be set into an ordinary candlestick or holder. A further object is to provide improved means for mounting such a decorative candle in any ordinary candlestick, whatever may be the dimension of the socket opening therein. The foregoing and other objects and advantages of the invention will more fully appear from the following detailed description taken in connection with the accompanying drawings, showing by way of example the preferred embodiment of the invention and the distinctive features of novelty will be pointed out in the appended claims.

Referring to the drawings:

Fig. 1 is a side elevation of a decorative candle embodying the invention;

Fig. 2 is a central vertical section of the decorative candle and also of the mounting thereof in a candlestick; and

Fig. 3 is a transverse section on line 3—3 of Figure 2.

10 indicates a transparent tube of glass or other suitable material, preferably having a length and transverse dimension approximating that of an ordinary candle, and having one end drawn inward with a reduced neck 11, having a relatively small opening therethrough, this drawn-in end also being made to simulate the appearance of a candle. This tube contains a quantity or colored fibrous material 12, preferably unwoven, such for example as silk, processed cotton, thread or yarn, floss and the like, or mixtures of any two or more of these. This material is inserted into the tube so that when in position it will be in a relatively compressed condition, and hence the inherent resiliency of the fibres will exert a resilient force which will press the fibres into intimate contact with the transparent walls of the container or tube. Short strands of this yarn or floss are extended outward through the restricted neck opening 11 and made to simulate a wick as indicated at 12. The other end, or bottom of the tube may be closed by a cork 13 pressed tightly thereto. I have found that the feature of closely packing and tightly compressing the yarn or floss in the tube is of great importance for decorative ornamental purposes, since the sheen and lustre is greatly enhanced by the flattening and pressing of the yarn against the glass, and I desire to protect this feature of the invention broadly. The yarn or floss employed in the tube may be all of one color, but particularly beautiful and variegated effects are obtainable by commingling two or more properly selected colors. The compression of the yarns against the sides of the glass produce a sort of grain somewhat resembling wood, and also exhibiting decorative scrolls, and an endless variety of fanciful designs resulting from the undulation of the fibres as they are inserted in the tube in relatively compressed condition. The invention also comprises means for mounting the decorative candle described, in an ordinary candlestick or holder. It will be understood that this would ordinarily be a matter of difficulty on account of the unyielding property of the glass, and also because of the fact that there is no uniformity of size in the sockets of candlesticks. To obviate this difficulty I provide a stout pin 14, which may have a head 15, similar to an ordinary hat pin, and embed this pin in the packed textile yarn, with its outer pointed portion 14^a extending some distance through the cork 13. A cork 16 is selected of a size to fit closely within the socket of the candlestick 17 to which the candle is to be applied. By then stabbing the pointed end 14^a of the pin downward into this cork 16, the candle is securely held in proper upright position in the candlestick and without requiring any other support or attention. I am aware that

the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

10 Having described my invention, what I claim as new and desire to secure by Letters Patent is:

1. A transparent tube filled with tightly compressed, colored textile fibre, made up 15 to simulate a candle or the like, and with strands of such yarn led through a restricted opening in one end of the tube to simulate the appearance of a candle wick.
2. As a decorative article, a transparent tube filled with tightly compressed, textile fibre.
3. A transparent tube, produced to simulate a candle with one end drawn inward and having a restricted opening therethrough, said tube filled with tightly compressed, fibrous material with strands of such material extending outward through said end opening to simulate a candle wick.
4. A transparent tube, produced to simulate a candle with one end drawn inward and having a restricted opening therethrough, said tube filled with tightly compressed, textile material with strands of such yarn extending outward through said 35 end opening to simulate a candle wick, and means for mounting said tube in a candlestick or the like embodying a member selective as to size adapted to be pressed into the socket of the candlestick, and a pin 40 projecting from the end of said tube adapted to be forced into said member.

5. A decorative article of manufacture comprising a hollow transparent body portion, and colored unwoven fibrous material within said body with the fibres adjacent the transparent walls of said body arranged in undulations and held in intimate resilient engagement therewith. 45

6. A decorative article of manufacture comprising a hollow transparent body portion and colored unwoven fibrous material within said body with the fibres adjacent the transparent walls of said body arranged in a variegated design and held in intimate engagement therewith by the inherent resiliency of said fibres. 50

7. A hollow transparent body containing colored unwoven fibrous material of substantial candle form in relatively compressed condition whereby the fibres are held in intimate engagement with the walls of said body, and a tassel like wick attached to the upper end thereof and extending therefrom. 60

8. A hollow transparent body containing colored unwoven fibrous material of substantial candle form in relatively compressed condition whereby the fibres are held in intimate engagement with the walls of said body. 65

9. A hollow transparent body containing colored unwoven fibrous material of substantial candle form in relatively compressed condition whereby the fibres are held in intimate engagement with the walls of said body, and resilient means associated with the lower end of said candle whereby said candle is adapted to substantially fit candlestick sockets of varying sizes. 75

In testimony whereof, I have signed my name to this specification.

ROBERT O. WOOD.
